W. CANN,

Mill Bolt.

No. 11,039. Fig. 1.

Patented June 6, 1854.

Fig. 2.

UNITED STATES PATENT OFFICE.

WILLIAM CANN, OF BLACK ROCK, NEW YORK.

CLEANING BOLTS OF FLOURING-MILLS.

Specification of Letters Patent No. 11,039, dated June 6, 1854.

To all whom it may concern:

Be it known that I, WILLIAM CANN, of the town of Black Rock, in the county of Erie and State of New York, have invented 5 a new and Improved Mode of Cleaning Bolts in Flouring or Grist Mills; and I do hereby declare that the following is a full, clear, and exact description thereof, reference being had to the accompanying drawings and to the letters of reference marked 10 thereon.

In the accompanying drawings Figure 1, is a perspective view of the chest showing the bolt and the cleaner as they are seen 15 when the mill is going, and the cleaner in operation, and Fig. 2, is a transverse view of the chest showing an end view of the bolt and shaft on which it turns, and an end view of the shaft to which the cleaner 20 is attached.

In the grinding of wheat in all flouring mills it is of the utmost importance that the bolts should be kept free from "beards" and other obstructions, which clog up the 25 meshes of the bolting cloth, so as to enable the mill to be run without cessation. In grinding spring or damp wheat, and wheat mixed with oats, the cloth of the bolt becomes pasted up, by the damp flour and 30 filled with the "beards" of the oats, so as entirely to obstruct the bolting. When bolts become obstructed in this way, the mill has to be stopped and the bolts cleaned by brushing or "shaving." This process 35 takes much time, and there is great danger of cutting and otherwise damaging the bolts by "shaving."

The object of my invention is to clean the bolts from all obstructions of every kind 40 without stopping the mill, or the grinding, and without resorting to the process of "shaving" and "bushing." It also does away with the necessity of the use of the "knocker" used in many mills.

45 The nature of my invention consists in providing the bolts used for bolting flour in flouring "mills" with an instrument which I call "cleaner" to be made of common cloth of any kind, or other flexible 50 material, which cleaner is to be attached to, and suspended from a shaft, or rod, running horizontally above and parallel with the bolt, thence falling over and coming in contact with the bolt, forces or knocks the 55 "beards" or other substances which obstruct the meshes of the bolting cloth back

into the interior of the bolt, whence they are carried off in their proper channel. This cleaner will perfectly clean the bolts when they become incapable of bolting flour by 60 reason of being pasted by dressing the flour made from damp wheat, or when the meshes of the bolting cloth become obstructed or clogged up by "beards" or other foreign substances. This cleaner entirely 65 does away with the necessity of stopping the mill for the purpose of cleaning the bolts by "brushing," "shaving" or any of the ways in use among millers; it saves the time usually spent in so cleaning the 70 bolts; prevents the exterior wear and tear occasioned to the bolt by shaving and renders the grinding of damp wheat and the bolting of flour made therefrom perfectly 75 feasible.

To enable others skilled in the art to make and use my invention I will now describe its construction and operation.

I construct my bolts in any of the forms in common use among millers, and affix over 80 the bolt a rod, or shaft, which may be made either stationary or revolving, running the entire length of the bolt and horizontally with it, as is shown in letter "B," of the accompanying drawings, to 85 which rod or shaft, I attach a piece of cotton, woolen or other cloth, or other flexible material, of the same length as the bolt which it is designed to clean, as shown in the accompanying drawings in letter 90 "C," which "cleaner" may be twelve, or fifteen inches in width, or of such other width as the size of the bolt may render necessary. The "cleaner" being thus attached and suspended as shown in letters 95 "B" and "C" in the accompanying drawings, in Fig. 1, in such a manner and at such a distance from the bolt as to allow the "cleaner" to come in contact with and bear upon the bolt, a light attrition is produced 100 by which the "beards" and other substances are prevented from lodging in the meshes of the bolting cloth, and are forced back into the interior of the bolt whence they are carried off in the channel made for their 105 discharge.

From the lightness and flexibility of this cleaner it may be constantly used without any damage to the bolt, and when not used it may be turned over the rod or shaft "B" 110 in the accompanying drawings.

I surround the bolt also my cleaner by

a box, or chest, as shown in the accompanying drawings in letter "G," in the manner commonly adopted in grist mills.

In the accompanying drawings letter 5 "D" represents the bolt; letter "E" the door to the chest; letter "F" the space inside the chest; letter "A" the end of the shaft on which the bolt turns.

What I claim as my invention and desire 10 to secure by Letters Patent is—

The application to flouring bolts, of a "brush," or "cleaner," as herein described, which will prevent the bolts of flouring mills from becoming clogged up with and

obstructed by "beards" and other substances which are contained in almost all wheat, and which will keep the bolts clean and free without the necessity of "shaving" and "brushing" the bolts, using for that purpose the aforesaid cotton, woolen, or 20 other cloth, or other flexible material, substantially the same and which will produce the desired effect.

WILLIAM CANN.
